[57] **CLAIM**

The ornamental design for a shroud-enclosing panel for the wall of the interior of an aircraft, as shown and described.

DESCRIPTION

FIG. 1 is a front perspective view of a shroud-enclosing panel for the wall of the interior of an aircraft without monitor shrouds attached;

FIG. 2 is a perspective view thereof with one monitor in an open condition and one monitor in a closed condition;

FIG. 3 is a perspective view thereof with both monitors in closed condition;

FIG. 4 is a perspective view thereof with both monitors in opened condition;

FIG. 5 is a cross sectional view taken along the line of FIG. 1; and,

FIG. 6 is a side elevational view thereof.

FIG.1

FIG. 2

FIG.3

FIG.4

FIG.5

FIG. 6
